SELF-SUSTAINING CULVERT

Edward J. Hatch, Creston, Iowa, and Eugene A. Stringer, Omaha, Nebr., assignors to Nebraska Bridge Supply and Lumber Company, Omaha, Nebr., a corporation of Nebraska

Application August 15, 1935, Serial No. 36,426

6 Claims. (Cl. 138—79)

The present invention relates to culverts and like conduits which are usually embedded or covered with earth to permit the flow of water or sewage therethrough, and an object of the present invention is to provide a culvert which is durable, of strong construction and which may be produced and installed at low cost, and wherein the parts thereof may be assembled quickly and conveniently when building the culvert or conduit.

Another object of the invention is to provide an improved means for conveying small streams of water through embankments under highways, streets, and roads, and wherein the same will be adequately supported.

Another object of the invention is to provide improved bracing means in the construction of a wood culvert wherein the culvert may be economically set up wherever required.

Another important object of the invention is to provide a culvert or conduit in sections made up each of tongue and grooved end members so constructed that the sections of the culvert may be built at a factory for ready assembling at the location of installation and also wherein the culvert may be quickly and easily taken apart or knocked down when its use is no longer required.

As heretofore practiced in the art, various expedients have been resorted to for securing culvert sections together, such as dovetailing the ends of abutting pieces to reduce the manufacturing and assembling cost. Such prior devices and constructions however are easily disarranged or moved out of line by external pressure of the earth and the like enclosing the culvert, and it is an object of this invention to provide a culvert construction having transversely disposed braces which function to hold the culvert against distortion or separation as to its parts under lateral and other strains.

Other improvements and novel features in the construction and arrangement of the parts will be brought out in more detail in the following description which, for a clear understanding of the invention, is to be considered in connection with the accompanying drawing forming a part thereof, and wherein is disclosed for the purpose of illustration one convenient and satisfactory embodiment of the invention.

In the drawing, Figure 1 is a perspective view of a culvert or conduit constructed according to the features of the present invention.

Figure 2 is a detail side elevation of one of the bracing culvert sections.

Figure 3 is a detail face view of another culvert section located adjacent the bracing section and showing the filler strips or tongues thereon.

Figure 4 is a detail face view of a third section of the culvert showing the diagonally disposed beveled butt ends of the parts thereof, and

Figure 5 is a fragmentary section through the culvert showing adjacent sections in face abutting relation.

Referring now to the drawing, the culvert is preferably constructed of wood of suitable standard dimensions such as 2 x 4's, 2 x 6's and the like depending upon the size and weight to be supported. The culvert is made up in a number of sections of substantially right angular form and the majority of the sections are of the construction shown in Figure 4. In this figure the section is made up of a plurality of side pieces 10 each having a squared end 11 and a beveled end 12. The beveled ends 12, at opposite corners of the sections, of the adjacent side pieces 10 are disposed in abutting relation and the intermediate corners of the section have the squared ends 11 disposed in right angular abutting relation. The beveled ends 12 are preferably on a 45° angle so as to interbrace and hold the side pieces in substantially rectangular relation. These frame sections of the culvert are disposed in any desired number in face to face engagement as shown in Figure 1 and the frame sections are alternately disposed in opposite relation to each other with respect to the beveled ends 12 of the side pieces so that the opposite and intermediate joints between the side pieces 10 are arranged in offset and overlapping relation. The side pieces may be provided with openings 13 therethrough for the reception of nails, bolts, rods or the like adapted to be used for holding the sections in laminated form to produce the body of the culvert of the desired length.

At suitable points throughout the length of the culvert the same is provided with bracing sections such as shown in detail in Figure 2. Each bracing section is provided with a lower beam 14 which is of considerably greater length than the bottom of the culvert so as to project from opposite sides thereof as shown in Figure 1 to hold the culvert from turning or twisting under lateral strains. This bottom or base section 14 is provided with side pieces or uprights 15 adapted to register with the sides of the culvert and which support across their upper ends a cross or top piece 16 which preferably extends slightly beyond the outer faces of the uprights 15. The top and bottom sections or beams 14 and 16 are prefer-

ably of twice the width of the side pieces 10 of the culvert sections and the uprights 15 are also of the same width as the side pieces 10 but are offset between the bottom and top beams 14 and 16 so as to lie flush with one side of the bracing section and to thus engage in face to face contact with the adjacent culvert section. As shown in Figure 3 the adjacent culvert section is provided with a pair of filler or tongue strips 17 which are secured to the side pieces 10 at the sides of the culvert and which are adapted to fit into the recess of the bracing section to fill in the space thereof and to insure the anchoring of the brace section in true alignment with the culvert sections.

Diagonally disposed sway rods 18 are disposed at opposite sides of the bracing section between the outer ends of the top piece 16 and the outer ends of the base beam 14, wedge shaped washers 19 being interposed between the clamping nuts of the rods 18 and the respective upper and lower faces of the beams 16 and 14. As shown in Figure 1, two of the bracing sections are employed. It is understood however that any desired number may be used depending upon the length of the culvert and the weight to be imposed thereon. The culvert sections, the bracing sections and the tongues may all be clamped or secured together by nails, bolts, rods or the like so as to rigidly hold the sections together and provide a rigid laminated culvert body and one which is substantially sealed against seepage through the walls thereof.

It is apparent that the various sections may be constructed at a factory or the like and assembled at the location of installation of the culvert. The culvert body may also be manufactured in laminated sections of desired length and assembled on the site of installation.

When it is desired to remove the culvert or to change the position thereof, such operation may be readily effected by separating the various sections to a more or less extent as desired so that the culvert may be knocked down, transported and readily reset at the new location.

The offsetting of the corner joints of the culvert sections provides alternately overlapping joints so as to increase the strength of the culvert and distribute the stresses imposed on the side pieces 10 evenly throughout the culvert structure. The advantage of the diagonal butt joint is had and also the advantage of the square end butt joint is had and these joints being overlapped throughout the length of the culvert insure a strong and sturdy construction wherein the joints are interbraced one against the other.

It will be obvious that various changes and modifications may be made in the construction, combination and arrangement of parts which could be used without departing from the spirit of our invention and we do not mean to limit the invention to such details except as particularly pointed out in the claims.

Having thus described our invention what we claim and desire to secure by Letters Patent of the United States is:—

1. A culvert comprising a laminated body of frames, each frame having opposed diagonal corner joints and intermediate square joints and with the diagonal and square corner joints overlapping to offset the planes of meeting of the side portions of the frames and to reinforce the joints against one another throughout the body, and the alternate frames being offset as to their joints with respect to the intermediate frames

throughout the body, and sway bracing frames interposed between said first frames for supporting the body against lateral crushing.

2. A culvert comprising a plurality of rectangular frame sections disposed in face to face contact throughout the length of the culvert, each of said frames having diagonal butt joints at opposed corners and intermediate square end butt joints, and the frames being alternately offset axially with respect to the intermediate frames with the diagonal joints overlapping the squared end joints to strengthen the culvert throughout its entire length, and bracing sections interposed between said first sections and having bottom extensions projecting beyond the opposite sides of the culvert body and including sway braces extending from said projecting ends to the upper portions of the bracing sections to support the body against lateral crushing.

3. A culvert comprising a laminated body portion of frames, each frame having corner joints with their planes of contact disposed in angular relation to each other about the corners of the frame and the intermediate frames being offset axially relatively to the alternate frames to overlap said joints throughout the length of the culvert, and bracing sections interposed between said first sections and having diagonally disposed rods extending beyond the opposite sides of the culvert body to brace the same and having recesses in one side, and filler tongues interposed in said recesses and adapted to be secured to the adjacent main sections of the culvert to interlock the same with the bracing section.

4. A culvert comprising a laminated body portion of rectangularly constructed frames having intermediate and alternate abutting ends in different angular relations, said frames being offset axially with respect to each other throughout the length of the culvert body for overlapping said corner joints, a bracing frame interposed between said first frames and having a bottom beam extending beyond the opposite sides of the culvert body and having a top beam projecting beyond the opposite sides of the body, diagonal brace rods interconnecting the projecting ends of the bottom and top beams of the bracing section, said bracing section having uprights between the beams thereof of less thickness than the beams and providing recesses in the side of the bracing section, and filler tongues carried by the adjacent body sections of the culvert and projecting into said recesses for interlocking the body and bracing sections and closing in the sides of the culvert.

5. A culvert comprising a plurality of rectangular frames having alternate and intermediate and abutting joints disposed in different angular relations, said frames disposed in face to face contact throughout the body of the culvert and with said corner joints disposed in overlapping relation throughout the length of the culvert, a bracing section interposed between said frames and having top and bottom beams projecting beyond the sides of the culvert and having uprights interconnecting the beams and being of less width than the beams to provide recesses in the side of the bracing section, filler tongues fitting in said recesses and adapted to be secured to an adjacent body section of the culvert for holding the latter in line with the bracing section and sealing the latter in the culvert, and diagonally disposed bracing rods arranged exteriorly of the

culvert body between the opposite ends of the beams of the bracing section.

6. A culvert comprising a laminated body of frames, each frame having opposed diagonal joints and intermediate square joints, the intermediate and alternate frames positioned to dispose diagonal joints across the square joints throughout the length of the culvert, said frames

having alining apertures throughout the length of the culvert, means engaging through the apertures to secure the frames in horizontal alignment, and bracing means interposed between certain said frames for supporting the body against lateral crushing. 5
